(57) **CLAIM**

I claim the ornamental design for a hat, as shown and described.

DESCRIPTION

FIG. 1 is a front perspective view of a first embodiment of a hat in accordance with the present invention;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof;

FIG. 8 is a front perspective view of a second embodiment of a hat in accordance with the present invention;

FIG. 9 is a front elevation view thereof;

FIG. 10 is a left side elevation view thereof;

FIG. 11 is a rear elevation view thereof;

FIG. 12 is a right side elevation view thereof;

FIG. 13 is a top plan view thereof; and,

FIG. 14 is a bottom plan view thereof.

The broken lines showing the remainder of the hat are directed to environment. None of the broken lines form a part of the claimed design.

1 Claim, 8 Drawing Sheets
